UNITED STATES PATENT OFFICE.

HARRY Y. ARMSTRONG, OF SYRACUSE, NEW YORK, ASSIGNOR, BY MESNE ASSIGNMENTS, OF ONE-HALF TO AMERICAN MACHINE AND FOUNDRY COMPANY, A CORPORATION OF NEW JERSEY.

WRAPPING MACHINE.

Application filed July 22, 1924. Serial No. 727,425.

This invention relates to improvements in wrapping machines of the general type shown in my United States Letters Patent No. 1,626,379, granted April 26, 1927; and refers more particularly to improvements in the means for feeding the wrapper web in position to be positioned on or assembled with the article preparatory to the wrapping operation; to novel means for cutting the web after the article has been wrapped in and the web is laid and held on the article; to a novel guide for guiding the web in its travel toward the wrapping mechanism, and constructed also to serve as a guard for a severing knife, the latter preferably fixed, so that said guide becomes a guide and knife guard at the proper time, where it serves to unsheathe the knife and allow the knife to sever the web, and to other and further improvements in the details of web feeding, web wrapping and operating mechanism, looking toward simplification of the mechanism and reducing its cost of construction.

In the drawings showing the essential parts of one embodiment of the invention:

Figure 1 is a side view of the machine, with parts omitted.

Figure 2 is a top plan view with parts broken away.

Figure 3 is a plan section showing the frame and operating mechanisms.

Figures 4 and 5 are plan views of the pivoted article centering mechanism for the end tucker blades.

Figure 6 is a detail of the article feed plunger and its operating mechanism.

Fig. 6^a is a detail of the transfer element actuating cam.

Figure 7 is a detail of the package ejector and its operating mechanism.

Figure 8 is a detail of the web feed.

Figure 9 illustrates the web severing knife guard and its operating cam.

Figure 10 is a fragmentary plan view of an adjustable guide for the web.

Figure 11 is a section on the line 11—11 of Figure 10.

Figure 12 is a top plan view of the web severing knife and the web guide and knife guard.

Figures 13 and 14 are sections on the line

13—13 of Figure 12, with the parts in different operative positions.

Figure 15 illustrates parts of the castings which carry one pair of the end flap folding blades.

Figure 16 is a detail section on the line 16—16 of Figure 15.

Figures 17 to 21 inclusive, illustrate the several steps of wrapping the article.

As shown in the drawings, 22 designates the side and end members of a skeleton base supported on legs 23 having upward extensions 24, said extensions being connected by cross members 25, 26, which latter support longitudinal side members 27.

The article to be wrapped is fed by a feed plunger 31 from a support 30 to the receiving end of a vertically swinging transfer element 32 that is pivoted on a shaft 34 to swing at its free end between the plane of said support 30 and the receiving end of a runway 45 over which the wrapped articles are discharged. Said transfer element is swung on its pivot through the agency of a lug 28 having a roll 29 that travels in a cam track 35 of a cam member 35 fast on a rotatable shaft 36 and driven by intermeshing gear 50 and pinion 51, the latter fixed to a power shaft 51' (Figures 1 and 6^a).

The feed plunger 31 is operated by mechanism consisting of a crank arm 36 fast to a transverse rock shaft 39, the one end of which is fixed to a crank arm 41 to which is pivotally connected the rear end of a link 40, the front end of which is guided on the crank shaft 36, and is provided with a roll 42 which travels in a cam track 43 in one face of a cam disc 44 that is fast to said shaft 36. The rear end of said link 40 being pivoted to the crank arm 41 of the rock shaft 39, causes the crank arm 38 to give reciprocating movement to the plunger 31.

The article and web are forced onto the transfer element against a spring-pressed gripper 130, also carried by the transfer element, and which serves to hold the rear fold *w'* on the article. Said gripper is guided by engagement of its shank 131 with suitable guides 132, 133 on the transfer element, and is held normally in its rearmost position by a spring 134 fixed at one end to a lug on said

shank and at its other end to an upstanding lug on the rear guide bar 132; a stop 131 limiting the total rearward movement of said gripper.

5 The wrapped articles are discharged from the transfer element on and over the runway 45 by a bifurcated pusher 55 (Figures 1, 2 and 7) suspended from a cross shaft 56 that travels at its ends in guides 57 of the upper side frame bars 27; and said pusher is operated by a link 60 pivoted at one end to said shaft 56 and at its other end to a crank arm 61 that is fast on the shaft 34, said shaft 34 having a short crank arm 63 that is pivoted 10 to a link 64 (Figures 1 and 7) which has a cam roll 65 that travels in a cam track 66 of a cam 67 fast to said shaft 36, looped to be guided by said shaft.

The article A is pushed by the plunger 31 20 from the support 30 onto the rear end of the transfer element 32 when the latter is swung down into the plane of said support 30, and the moving article carries with it a portion of the web W that was theretofore draped

25 across the path of said article (Figure 17). The web W, in the end of which the articles are wrapped, is drawn from a reel W' carried by the frame and thence over a guide pulley 68 and over a table 69 above the support 30, where it is guided between laterally adjustable gauges 70 mounted on a right and left hand screw shaft 71 to adjust the machine to different web widths (Figures 10 and 11). A rocking eccentric back stop 72 30 prevents backward withdrawal of the wrapper at all times; and a brake bar 73 (Figures 1 and 10) may be employed and operated in suitable timed relation to the web severance period to prevent tendency of the 35 web being drawn forward during the severance period.

The web is initially trained from the table 69 beneath a web feed roll 75 carried by the free front end of a swinging arm 76 that is vibrated vertically across the front of the support 30 (Figure 1) to drape the web across the path of the article to be wrapped (Figure 17). The hub 77 of said arm 76 is pivoted to a transverse rock shaft 77', mounted in a bracket 77. A link 79 is adjustably pivoted at one end to the slotted end of a crank 80 integral with the hub 77 and has looped guiding engagement at its other end with the shaft 36. Said link carries a cam roll 81 which travels in a track 82 of a cam 83 fast on the shaft 36 to vibrate said lever 76 and carry the web feed roll through the arc indicated in Figures 1 and 8, by the full and dotted line positions of the roll 75, in each rotation of the shaft 36 and therefore in each cycle of operation of the machine.

When the article passes onto the transfer element, it carries with it a loop of the web end to partly wrap the article therein to 60 produce a partial bottom fold w, a front

fold w' and a top fold w² (Figure 18). There is also produced in this movement end flaps w³ and lower and upper triangular part flaps w⁴ and w⁵, respectively; said flaps being formed by the faces and the bottom 70 and top edges, respectively, of flap folding blades 85 that are carried by and move with the transfer element to give trough shape to the latter. When the free end of the transfer element and the blades 85 and the partially wrapped article are swung upwardly, they are moved between other end flap folding blades 86 that flank the receiving end of the runway and endwise overlap the blades 85 (Figures 1 and 2). The blades 86 are 75 supported at their rear ends on pivot brackets 111 whose pivot bolts 87 extend through slots 87' in the cross frame piece 26, whereby the pivots can be adjusted towards and away from each other, and the 80 blades 86 are allowed to swing on said pivots against the action of a restraining spring 110 (Figure 2). This gives adjustment for length.

The blades 85 are fixed at their front ends to brackets 85', each having a pair of outwardly extending stems 114 that slidingly engage apertures in the rear arms of castings 102 in such a manner that the blades and their brackets can be moved towards 90 and from each other and can be locked to the castings by screws 116. This is one adjustment for the blades 85 for the lengths of articles. Said castings are pivoted at 95 their front ends on studs 103 which extend through sleeves 103' and the studs of the castings are adjustably fixed in slotted brackets 120 of the machine, whereby the pivot ends of the castings can be adjusted towards and from each other, in the manner 100 of the pivot studs 87 for the blades 86 to give another adjustment function to articles of different length. The rear ends of the arms and the blades 85 are spread away 105 from each other, when the transfer element it at the lowermost part of the arc of its movement by engagement of rollers 105 with side cams 106 (Figures 1, 4 and 5) that are fixed to opposite sides of the gear 50, and said blades begin to swing toward each other 110 under the action of the spring 110 (Figure 2) when the article is moved partially onto the transfer element (Figure 5). The mounting castings 102 are supported on and 115 move with the transfer element, and the transfer element is longitudinally cut away to permit the gear 50 to extend upwardly therethrough. The free ends of the blades 85, 86 are swung laterally in unison, through the action of the spreading cams 106, by 120 means of lugs 107 on the front ends of the blades 86 which overlap and slide vertically along the elongated, upright curved bars 108 fixed to the adjacent ends of the blades 85; the said lugs and bars cooperating with 125

the spreading cams and said tensile spring 110 to maintain the free ends of the blades 85, 86 equally pressed toward the wrapped article ends to iron the end flaps thereof 5 in all positions of adjustment of the pivot pins or studs 87 and 103. Equalizing arms 118, fast to the pivot ends of the castings 102, overlap each other, one carrying an eccentric pin 122 which extends through 10 a slot in the other. This connection compels equal movement of the blades 85, 86 and positively centralizes the article on transfer element and runway when the blades are forced toward each other, from the position 15 shown in Fig. 5, against the end flaps of the article. Compensating gearing may be substituted for the slotted arm connection. The eccentricity of the pin 122 enables exact centering of the article to be obtained relatively to center line of the machine.

After the partially wrapped article has been delivered by the transfer element and the web partially folded thereon, and with the blades 85, 86 spread apart, the spreading cams 106 pass gradually away from the 25 rolls 105 of the pivot castings so as to permit the free ends of the flap folding blades to move gradually together under the action of the spring 110, and thus cause the blades 30 to press on the end flaps of the article for which the machine is adjusted to closely set the said flaps on the article ends. Stops 113 adjustably fitted to the transfer member 32 by the slots shown in Figure 2 limit the total 35 inward movement of said castings 102 for each adjustment of said stops.

When the free or rear end of the transfer element and the partially wrapped article thereon are swung upwardly, the triangular flaps w^5 (Figure 18) are folded down by the flap folding blades 86 toward the article end to the position indicated in Figure 19 to constitute a part of the top flaps w^6 , which 40 said top flaps will be completed in the further folding operation by laying thereover the triangular flaps w^7 which, during the raising movement of the transfer element, pass through oblique slots 87 of the folding blades 86. When the transfer element is 45 thus lifted, it also pulls the fold w^8 down over the rear side of the article, and the end extensions of said fold pass through slots 87, with the triangular flaps w^7 to produce 50 the configuration of the flaps shown in Figure 19. Thereafter, when the partially wrapped article is forced rearwardly from the transfer element onto the runway, the depending portion w^9 of the web is folded 55 underneath the article in overlapped relation to the fold w^8 , and at this time the triangular flaps w^7 are folded, with the end extensions of the folds w^8 over the flaps w^6 , w^8 to produce the full flaps w^{10} of Figures 20 and 21. During this movement also the triangular 60 flaps w^{11} , which were formed between the

flaps w^{10} and the triangular flaps w^4 , are thrown upwardly against all of the flaps to produce the final end flaps w^{12} of Figure 21 by the passage of the opposing triangular flaps w^4 , w^{11} through oblique slots 92 formed 70 between the rear oblique edges of the blades 86 and corresponding oblique edges 93 of plates 94 which lie in the planes of the blades 86 and flank the runway rearwardly beyond said blades. The side plates 94 of the runway hold the end flaps together and on the article ends until brought into contact with side electrically heated hot plates 96 that rise from a long transverse bottom hot plate 98, which constitute trough-like extensions of 80 the runway, and heat seals the folds and flaps when the wrapper material is wax paper. Paste applying and closing mechanisms may obviously be substituted for the heat sealing devices. The rearmost part 99 85 of said bottom, and corresponding portions 100 of the side plates are ribbed to chill and set the sealing wax or paste of the wrapper material.

The side hot plates 96, the said plates 94, and the side plates 100 are all connected together as lateral symmetrical units by elements 101 and are adapted to be adjusted simultaneously inwardly or outwardly through the medium of a right and left hand screw 125 which has suitable rotative bearing in the main frame and engages nuts 126 movable with said units and is turned by a hand wheel 126'. Springs back the plates 94 and hot plates 95 to resiliently hold the end flaps against the article while being guided and closed.

In operation the end flap folding blades 85, 86 are swung away from each other as the articles are moved from the support 30 to the transfer element, such spreading being brought about by the spreading cams 106 acting on the rollers 105 of the pivot castings 102 and the coaction of the bars 108 of the blades 85 with the lugs 107 of the blades 86, swinging the latter on their pivot studs 87, and as the side cams 106 pass away from the rollers 105, the spring 110 causes the blades 85, 86, to yieldingly wipe the end flaps to preliminarily hold them together before 110 passing onto the hot plates 96; and by reason of the fact that the last laid bottom fold w^9 is a trailing fold it will cause the side wrapping to be held tight on the article until it reaches the bottom runway 45.

The web is severed after the half bottom fold has been pinched between the article and the bottom of the runway (and thereby avoid a slackening of the wrapper away from the article) by the stationary knife 90 at the bottom of the runway and normally guarded from contact with the web by a transverse web guide and knife guard 140 which normally lies under the knife 90 (Figures 1, 12 and 13) and is adapted at 139

the proper time to be moved rearwardly to expose the knife so as to cut the web (Figures 9 and 14). If the brake bar be employed, it will at this time be moved downwardly to pinch the web between it and the plate 69 and thus brake movement of the web as it is being severed. Said guide and guard 140 is carried by the upper ends of levers 145 pivoted to a shaft 146 in the frame. The levers are swung on their pivots to control the guide and guard bar by a link 148 pivoted at its rear end to a crank arm 149 fast to the rock shaft 146 exterior to the frame bar 22 (Figure 1). The forward end 15 of the link has thereon a cam roll 150 engaging with a cam track 151 in a cam 152 fast on the shaft 36 exterior to the frame bar 22. The cam 152 is adapted to be angularly adjusted on the shaft 36 by the set screw 152' so as to vary the time of throw of the 20 guide and knife guard bar and thereby regulate the width of the last half bottom fold w^9 and the amount of its overlap on the first half bottom fold w . Likewise, the slotted 25 connection of the link or bar 79 to the crank arm 80 of the roll carrying arm 76 permits of adjustment which will vary the extent of lap of the first bottom half fold w on the article and to adjust for different width 30 articles.

It will thus be understood that Figure 1 shows the parts in position with an article partially side and end wrapped preparatory to forcing it on the runway to complete side 35 and end wrapping and that the knife will not be uncovered to sever the web until after the last bottom half fold w^9 is pinched between the article and the bottom of the runway. It will also be understood that before 40 the web is severed the roll 75 is moving down to carry a loop of the web across the support 30, so that the web is not only drawn tightly on the article, but additional web length is being drawn from the roll W'. When the 45 web is severed by the knife the roll 75 will straighten the free end of the web to the position shown in Figure 17; the lowest dotted circle in Figure 1 denoting the end of the throw of said web feed roll; and the 50 descending transfer element will complete said drape.

It will also be noted that the article and web are fed in three stages,—the first by the plunger 31 to move the article and a loop of the web onto the transfer element 32; the second when the free end of the transfer element is lifted to the plane of the runway, and the third when the pusher forces the article and web onto and over the runway; 55 and that during all this time the article is being wrapped in the free end of the web. Practically the entire circumferential wrapping is effected before the severance of the web, and the end flap folding is partly 60 completed after the severance of said web. 65

The various adjustments enable a single machine to perfectly wrap or wrap and close articles of considerably varying dimensions and contours.

It will be furthermore observed that the different elements of the side and end folding elements may be made as standard or stock parts to be adapted to a standard frame and that adjustment of said elements can be made within or relative to each other 75 and the frame to adapt a single machine to wrapping articles of widely varying dimensions, within limits.

In the construction shown, it will be noted that the severing knife extends transversely 80 across the width of the runway and is fixed to the entering end thereof so as to constitute the receiving portion of the runway bottom end, as in the position shown in Figure 13. This disposition of the parts is 85 advantageous inasmuch as it constitutes a very compact assembly of the parts and provides a simple way of entering the partially wrapped package onto the runway to finish the trailing fold w^9 of the web end beneath 90 the article so as to prevent the wrapper from slackening away from the article after the severance of the web takes place and maintains a smooth circumferentially wrapped 95 package produced by a minimum use of paper. 100

I claim as my invention:

1. In combination, means for moving a web, a knife disposed transversely to the path of such web to sever the same, a web guide bar normally sheathing the edge of 100 said knife, and means for moving said bar relative to the knife edge to unsheathe the latter for severing operation.

2. In combination, means to move a web, a knife in position to sever said web, a web 105 guide bar normally sheathing said knife, and means for moving said bar transversely relative to said knife to unsheathe the same.

3. In combination, means for moving a web to be severed, a fixed knife having an 110 edge in position to sever said web transversely as it is moved past the same, a web guide bar normally extending longitudinally of and at its guiding edge laterally beyond the cutting edge of the knife, and means to 115 sheath said bar laterally away from said cutting edge.

4. In combination, means for moving a web, a knife having an edge in position to 120 sever said web as it moves past the same, a web guide bar normally sheathing said edge, and means to operate said bar between sheathing and unsheathing positions.

5. In combination, means for moving a web, a knife in position to sever the web as 125 it is moved past the same, a web guide bar normally sheathing said knife, a swinging arm to support said bar, means to swing said arm, and a cam to control swinging movement of said arm. 130

6. In combination, a fixed severing knife, means for moving a wrapping material past said knife in position to be severed thereby, a bar normally to sheath said knife, and means to shift said bar relative to said knife comprising a rocking crank arm, a shaft to which said arm is fixed, an arm to carry said bar and fixed on said shaft, a cam, and operative connections between said last arm and said cam. ¹⁰
- In witness whereof I claim the foregoing as my invention, I hereunto append my signature this 14th day of July, 1924.

HARRY Y. ARMSTRONG.
